Richard Oliver,

Attorney

UNITED STATES PATENT OFFICE.

HERBERT OVER, OF SILTON, SASKATCHEWAN, CANADA.

AUTOMATIC-RELEASE COUPLING.

1,294,696.

Specification of Letters Patent. Patented Feb. 18, 1919.

Application filed August 19, 1918. Serial No. 250,530.

To all whom it may concern:

Be it known that I, HERBERT OVER, a citizen of the United States, residing at Silton, in the Province of Saskatchewan and Dominion of Canada, have invented certain new and useful Improvements in Automatic-Release Couplings, of which the following is a specification.

My invention relates to new and useful improvements in an automatic release coupling.

The principal object of the invention is the provision of an automatic release coupling particularly adapted for connecting a plow, cultivator, or other like implements to a tractor whereby the same will be automatically uncoupled should a rock or other obstruction be engaged.

Another object of the invention is the provision of means for adjusting the coupling to regulate the point at which the uncoupling will take place.

A further object is the provision of means whereby the parts may be disconnected and replaced in case of breakage or becoming worn.

With these and other objects in view my invention consists of the novelty, details in construction and arrangement of parts as will be more clearly understood from the following specification and drawings in which:—

Figure 1 is a side elevation.

Fig. 2 is a longitudinal vertical section 35 through the casing forming a part of my coupling.

Fig. 3 is a transverse section on the line 3—3 of Fig. 2 looking in the direction of the arrow, and

Fig. 4 is a transverse vertical section on the line 4—4 of Fig. 2 looking in the direction of the arrow.

In the drawings the numeral 1 indicates a casing which is closed at one end as indicated at 2 and open at the opposite end. The closed end 2 is provided with a central opening the purpose of which will be presently described. A longitudinally extending rib 3 is formed on the top of the casing and is provided with a plurality of longitudinally spaced openings 4. A loop member 5 is secured to the rib 3 by means of a bolt 6 which passes through the opening 4 and through eyes formed in the end 7 of the looped member. As is indicated more particularly in

Fig. 3 of the drawings the ends 7 of the loop member 5 are preferably flattened so as to snugly engage the sides of the rib 3.

The casing 1 is provided on each side with a longitudinally extending opening 8 more particularly illustrated in Fig. 1 of the drawings and this opening extends from a point adjacent the closed end of the casing through the open end thereof.

A rod 9 is adapted to pass through the central opening in the closed end 2 of the casing 1 and extends longitudinally of the interior of the casing as more particularly indicated in Fig. 2 of the drawings. The inner end of the rod is threaded as indicated at 10 and a nut 11 is adapted to be received on the threaded end. The opposite end of the rod is provided with the enlarged ears indicated at 12 and these ears are spaced apart so as to receive the flattened end 13 of a hook member or shackle 14 which is pivotally connected to the rod by means of a pin 15 which extends through the ears 12 and end 13. As indicated more particularly in Figs. 1 and 2 of the drawings the ends of the hook member overlie the top of the casing and rib and extends longitudinally thereof. The outer end of the hook member is preferably turned up slightly as indicated at 16 and the loop member 5 is adapted to engage over the end of the hook 14 as shown and for the purpose as will be presently described.

A washer plate 17 is carried on the rod 9 adjacent the closed end of the casing, and a washer plate 18 is carried on the threaded end of the rod 9 and engages the inner space of the nut 11. The washer plate 18 is provided on each side with a lug or projection 19 which is adapted to pass through the longitudinally extending opening 8 in each side of the casing. A coiled spring 20 encircles the rod 9, within the casing 1 and between the washer plates 17 and 18.

A cap 21 is adapted to close the open end of the casing 1 and is secured in position by means of the threaded bolts 22 which enter threaded openings formed in the end of the casing as more particularly illustrated in Fig. 2 of the drawings. The threaded bolts 22 are provided with the enlarged head 23, whereby the bolt may be adjusted in position. It will be understood that the enlarged head 23 engages the outer face of the cap 21. An eye member 24 is formed integral with the cap 21 and is adapted to receive a link 110

25 by means of which the coupling is secured to the tongue or beam 26 of the plow, cultivator, or the like.

The coupling is connected to the tractor by 5 means of a link 27 which is engaged by the hook member 14 and may be secured to the tractor in any desired manner.

From the above detailed description of the construction of my coupling it is thought 10 that the advantages and mode of use will be understood. As previously stated the coupling is connected between the tractor and plow or cultivator and the tension of the coiled spring 20 is sufficient to allow the 15 tractor to draw the cultivator or plow through the ground until a large rock or other obstruction is engaged by the plow or cultivator. When such an obstruction is engaged the spring will be compressed as 20 the rod is drawn through the closed end 2 of the casing and the hook member 14 will be disengaged from beneath the loop 5. When the end 16 of the hook has passed the loop 5 the hook 14 will naturally drop 25 downwardly and thereby releasing the tractor from the coupling. The upwardly extending portions 16 on the end of the hook will necessitate the end of the hook being slightly bent downwardly when being engaged with or disengaged from the loop 5. The point at which the uncoupling takes 30 place may be adjusted by placing the loop 5 in the various longitudinally spaced opening 4. If the loop is placed in that opening nearest the opening in the casing then the spring will not be compressed as much, in releasing, as was the loop connected in the second or third opening. When connected in the fourth opening or that opening 35 nearest the closed end of the casing, the loop 5 will not allow the hook to be disengaged, but the coupling can then be used merely as a shock absorber.

Should any of the part be broken, on the 40 interior of the casing, it is only necessary to remove the bolts 22 and thereby remove the cap 21. When the cap has been removed then the nut 11 may be removed from the threaded end 10 of the rod 9 so that the 45 plate 18 may be disengaged and if desired the rod may be withdrawn from the closed

end of the casing. It will also be seen that when the cap 21 is removed then the coiled spring 20 or plate 17 may also be taken from the casing.

55

The foregoing description and the drawings have reference to what may be considered the preferred or approved form of my invention. It is to be understood that I may make such changes in construction and arrangement and combination of parts, material, dimension, et cetera, as may prove expedient and fall within the scope of the appended claims.

60

Having fully described my invention what 65 I claim as new and desire to secure by Letters Patent is:—

1. A coupling comprising a casing having a plurality of longitudinally spaced openings therein, a spring control rod connected 70 to the casing, a hook pivotally connected to the rod, and a loop adjustable in the longitudinally spaced openings and adapted to engage the hook.

2. A coupling comprising a casing, a rib 75 formed on the top of the casing and provided with a plurality of longitudinally spaced openings, a spring control rod carried by the casing, a hook pivotally connected to the rod, and a loop adapted to be 80 connected to the rib by means passing through the longitudinally spaced openings, said loop adapted to engage the hook.

3. A coupling comprising a casing closed at the one end and open at the opposite 85 end, the closed end provided with the central opening, a cap for closing the open end of the casing, an eye formed on the outer face of the cap, a rod extending through the central opening in the closed end of the 90 casing, washers carried by the rod within the casing, a coiled spring surrounding the rod between the washers, a hook pivotally connected to the rod, and a loop adjustably connected to the casing and adapted to engage the hook.

In testimony whereof I affix my signature in presence of two witnesses.

HERBERT OVER.
